US0D1041477S

(12) **United States Design Patent** (10) Patent No.: **US D1,041,477 S**
(45) Date of Patent: ** Sep. 10, 2024

(54) **BENDING SUPPORT FOR DISPLAY PANEL**

(71) Applicant: **SAMSUNG DISPLAY CO., LTD.**,
Yongin-si (KR)

(72) Inventors: **Seon Beom Ji**, Seoul (KR); **Jong Hyun Choi**, Seoul (KR); **Seung Min Lee**, Hwaseong-si (KR); **Dong Hwan Shim**, Hwaseong-si (KR)

(73) Assignee: **Samsung Display Co., Ltd.**, Yongin-si (KR)

(**) Term: **15 Years**

(21) Appl. No.: **29/740,154**

(22) Filed: **Jul. 1, 2020**

Related U.S. Application Data

(62) Division of application No. 29/688,608, filed on Apr. 23, 2019, now Pat. No. Des. 892,105.

(57) **CLAIM**

The ornamental design for a bending support for display panel, as shown and described.

DESCRIPTION

FIG. 1 is a front, top and right side perspective view of a bending support for display panel;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 5 Drawing Sheets
